(57) **CLAIM**

The ornamental design for a garment as shown and described.

DESCRIPTION

FIG. 1 is a front view of a garment;

FIG. 2 is a front left perspective view thereof;

FIG. 3 is a front right perspective view thereof; and,

FIG. 4 is a back view thereof.

FIGS. 1-3 show that a power button is located in the top middle part of the upper portion of the garment. The broken lines in the drawings represent portions of the garment that form no part of the claim.

1 Claim, 4 Drawing Sheets

FIG. 1

FIG. 2

FIG. 3

FIG. 4
